UNITED STATES PATENT OFFICE.

HUGH ALEXANDER THOMSON, OF GLASGOW, SCOTLAND.

INDEX-CLIP.

1,261,319.

Specification of Letters Patent.

Patented Apr. 2, 1918.

Application filed November 23, 1915. Serial No. 62,958.

To all whom it may concern:

Be it known that I, HUGH ALEXANDER THOMSON, a subject of the King of Great Britain and Ireland, residing at Glasgow, 5 Scotland, have invented Improvements in Index-Clips, of which the following is a specification.

My invention relates to index clips or signals adapted to be affixed to the leaves of 10 a book or to cards to indicate a particular order of sequence in reading or to mark special cards or pages.

The invention is particularly designed to provide a clip that can be easily and quickly 15 attached and which can be made to hold its grip with a spring derived pressure that can be manually augmented when desired. Other features in view are the provision of 20 a clip adapted to remain open when the parts are pressed into that position, and the provision of a clip in which lightness of weight in comparison to gripping power is a desideratum as for example when India paper is being dealt with.

25 To this end the clip comprises metal gripping members of a resilient character so offset and resistingly associated with one another as to cause material inserted between them to remain gripped with a force to produce which spring action in a direction perpendicular to the direction of the gripping force is utilized, such spring action being due to the resilience of the gripping members themselves so that no separate springs 30 are required.

The members of the clips according to the invention may be made in one or separately, appropriately connected, and may take various forms as will appear from a few examples now about to be described with reference to the accompanying drawings.

In the said drawings Figure 1 is a view of a spring sheet metal blank utilized in the production of the clip shown in side and 45 front elevation respectively in Figs. 2 and 3. Fig. 4 is a front view of a modified form of clip. Fig. 5 is a face view of one of a pair of members utilized in the production of the clip shown in Figs. 6 and 7 and Figs. 50 8 and 9 are views similar to Figs. 6 and 7 of a still further form of clip.

Referring first to Figs. 1 to 3, the clip is made of a blank stamped from spring sheet metal and sheared so as to leave two flexible strips *a* *b* attached, in this example, to a central disk piece *c* for carrying the index

number or color, the said strips in the act of stamping being so distorted as to be slightly and oppositely inclined to the initial plane of the blank. The free ends of 60 the strips *a*, *b* constitute spring lips *d* *e*.

The strips *a* *b* are offset in opposite directions at or about their centers as clearly seen at *f* in Figs. 2 and 3 to obtain inclined sliding and locking contacts and to assume 65 when in position a particular angle to provide a secure snap lock when closed and also an open retention position if desired. Thus in Fig. 1 the inclined edges *g* are destined to hold the strips *a* *b* in locked position 70 while the curved recesses *h* serve to hold the strips in open position. The offsets *f* permit the locking of the strips to be effected by pressing them together in the lip region, just as pressure exerted upon them in the region of the disk piece *c* will press them apart. The lip ends *d* *e* are preferably cut 75 obliquely to show a fish tail appearance. To produce a clip from the blank shown in Fig. 1 it is necessary to bring the lips *d*, *e* together by pressing the flexible strips *a*, *b* across and toward each other to contact the inclined sliding edges *g* and spring lock them together, the effect of this being to make the clip lips change their position and 80 become superposed to press against each other as shown in Fig. 3. The spring force developed by bending the strips *a*, *b* both across and toward each other is compound 85 in its resistance and the resultant pressure 90 so obtained is transmitted to produce a gripping and locking effect between the lips *d* *e* of the clip. The clip is opened as explained by pressing on the strips *a*, *b* above the offsets *f*, until the curved recesses *h* become 95 engaged; and the grip on the paper is regulated by the degree of finger pressure on the lips, it being understood that the spring action between the strips will cause the inclined edges *g* to remain in whatever position of 100 frictional engagement they may be pressed. The fish tail formation of the strips is maintained in a modified form when the clip is completed, as shown in Fig. 3, its purpose being to train or guide the paper into the 105 clip between the gripping members.

To make the clip as light as possible the central disk piece *c* for the index number may be dispensed with, the clip rim being used for index purposes in any suitable way. 110

An alternative method is to make the clip of two parts as shown in Fig. 4. Thus *i* is

a metal plate offset at f and slotted to receive a spring member which consists of a metal loop j shaped so as to coincide as nearly as possible with the outer edge of the plate i . Each leg k of the spring member is offset at f' where it passes through the slot in the plate and each offset is formed to give, when the clip is closed, a locking effect which is obtained by urging the offset 5 contact surfaces together, such a result being obtained for example by employing projecting abutment means. In the figure the abutment is shown in the form of curved edges m upon the plate i . The spring and 10 plate are suitably connected at one end as by riveting at n , the other ends forming the lips of the clip. By reason of the slotting and offsetting of the members part of member j extends to one side of the plate i and 15 part to the opposite side thereof and therefore the clip can be pressed at the upper part to remain open and also pressed at the lower part to grip the paper with a pressure which is adjustable in the sense that it can be augmented manually to overcome frictional 20 resistance which the spring action alone may be unable to do. The deflection of the spring provides spring pressure and such may be increased by the addition of one or 25 more tongues bent inward from the plate or 30 spring.

Another alternative method of construction would be to dispense with the plate and combine two skeleton springs with an index 35 plate of celluloid or other suitable light material inserted between them. A clip of this kind and also embodying the feature of supplementary spring tongue pressure above referred to is shown in Figs. 5 to 7. Thus in 40 Fig. 5 is shown a spring member offset in a similar way to that already described with reference to Figs. 1 to 3 and having a lip extension in the form of a spring o . Two such members, each however provided with 45 a reversely arranged rivet hole p of irregular shape, are assembled at opposite sides of an index plate r and secured together by a rivet s of a section corresponding to that of the holes p so that the requisite rigidity 50 to secure spring action equivalent to that of Fig. 3 is obtainable. The spring extension o of one member engages a notch t of the other member and the initial distance at x is less than that at y so that the spring extensions o are caused to exert a spring action 55 supplementing the main spring action. If desired, however, the joint at the rivet might be a loose one and the entire spring pressure derived from the extensions o . The 60 spring extensions o when the clip is in open position as shown in Fig. 6 are deflected from their initial position and shape which latter is advantageously one of a slightly permanent curvature in the gripping direction. In this way there is obtainable a pro-

gressive gripping action due to flexure of the tongues having a high degree of uniformity that enhances the gripping action upon material placed between the lips.

In Figs. 8 and 9 the clip comprises parts 70 i and j allied to those of Fig. 4, the plate i however having inclined and curved edges g , h , similar to those of Fig. 1 and spring tongues u similar to those already described, the said tongues passing through slots v in the member j and being adapted to alternately engage the plate i at either h or g in accordance with the opening and closing of the clip. Thus, as before, the plate i and member j are urged together or in a separating direction through the resistance offered by the edges g , h which however, in lieu of being engaged directly by the plate i are engaged by the spring tongues u that move in unison with such plate.

As will be understood in lieu of plate material, spring wire may in some cases be employed, and where weight is to be reduced as far as possible thinner sheet metal may be employed stiffened by stamping ribs thereon 90 in a manner well known.

What I claim is:—

1. An index clip comprising two resilient juxtaposed gripping members each having two flat portions and an intermediate offset 95 portion and means embodying coacting inclined edges integral with the gripping members and located in the offset regions aforesaid, adapted to act as a lock to hold said members open or closed, the two gripping 100 members being moreover intertwined whereby they are urged into closer intimacy under the action of force exerted by the material of the clip in a direction other than normal to the planes of the flat portion.

2. An index clip comprising two resilient juxtaposed gripping members each having two flat portions and an intermediate offset portion, means embodying coacting inclined edges integral with the gripping members 110 and located in the offset regions aforesaid, adapted to act as a lock to hold said members open or closed, the two gripping members being moreover intertwined whereby they are urged into closer intimacy under the 115 action of force exerted by the material of the clip in a direction other than normal to the planes of the flat portions, and equivalent edges integral with the gripping members, adapted to hold the gripping members 120 separated against the force aforesaid.

3. An index clip comprising two resilient gripping members each having two flat portions and an intermediate offset portion connecting the same, means embodying coacting inclined edges integral with the gripping members and located in the offset regions aforesaid, adapted to act as a lock to hold said members open or closed, the two gripping members being moreover intertwined 130

whereby they are urged into closer intimacy under the action of force exerted in a direction other than normal to the planes of the flat portions and tongues upon the gripping members engaging the offset portions and exerting force as aforesaid.

4. An index clip comprising two resilient juxtaposed gripping members each having two flat portions and an intermediate offset portion and means embodying coacting inclined edges integral with the gripping members and located in the offset regions aforesaid, adapted to act as a lock to hold said members open or closed, the two gripping members being moreover intertwined where-
- 10
- 15

by they are urged into closer intimacy under the action of force exerted by the material of the clip in a direction other than normal to the planes of the flat portions, the said members terminating in lips cut obliquely 20 and extending in different directions to produce a fish tail formation adapted to guide material into place between the gripping members.

Signed at London, England, this twelfth 25 day of November, 1915.

HUGH ALEXANDER THOMSON.
